ATTORNEY.

UNITED STATES PATENT OFFICE.

CHARLES R. FAY, OF AUBURN, NEW YORK.

PICTURE-HOOK.

SPECIFICATION forming part of Letters Patent No. 393,062, dated November 20, 1888.

Application filed June 4, 1888. Serial No. 275,925. (No model.)

To all whom it may concern:

Be it known that I, CHARLES R. FAY, of the city of Auburn, New York, have invented certain new and useful Improvements in Hooks for Pictures and other Analogous Articles, of which the following is a description, reference being had to the accompanying drawings, in which—

Figure 1 is a perspective view of my invention, and Fig. 2 represents one of the blanks from which the hook is bent.

The object of my invention is to furnish the double curved hooks of ordinary construction for use with a molding with means by which a single cord may be secured at its end thereto in such manner that it will support a weight without tilting sidewise. This I accomplish by furnishing the hook A B C with the ears d e, which are formed by the slots f f f f upon the sides of the blank from which the hook is made, the ears d e being bent forward to raise them above the plane B of the hook. Another slot, g, is cut from one side of the blank inward to its center, so that the cord may be

passed downward through it after being secured around the ears d e, as is shown in Fig. 1, and by this means the weight of any article suspended thereby is made to draw evenly downward upon the hook.

Having thus described my invention, what I claim as new, and desire to secure by Letters Patent, is—

1. The double-curved hook A B C, provided with projections d e, turned outward in opposite directions to form a cleat, the same being placed between the hooks A and C, substantially as described.

2. The double-curved hook A B C, provided with projections d e, turned outward in opposite directions to form a cleat, and having a slot, g, below said projections and extending from one side of said hook to its median line, substantially as described.

CHARLES R. FAY.
